ATTYS.

UNITED STATES PATENT OFFICE.

AUGUST Z. BOSE, OF WILLITS, CALIFORNIA.

FLOUR SIFTER.

Application filed April 30, 1923. Serial No. 635,488.

To all whom it may concern:

Be it known that I, AUGUST Z. BOSE, a citizen of the United States, residing at Willits, in the county of Mendocino and State of California, have invented new and useful Improvements in Flour Sifters, of which the following is a specification.

This invention relates to improvements in flour sifters and resides in the provision of a simply constructed, compact and efficient device of this nature which is arranged such that it may be taken apart for the purpose of readily and easily cleaning the parts thereof and may be operated without throwing the flour out of the sifter.

An object of the invention is to provide a sifter of the character described wherein the perforated bottom is close to the lower end of the sifter body and provision is made for the sifting of a greater quantity of flour than is the case with the ordinary sifter wherein the perforated bottom is spaced well upward from the lower end of the body.

Another object is to generally improve and simplify the construction and operation of flour sifters so as to render them superior to the ordinary sifter by way of simplicity and compactness of arrangement, ease of operation, strength and durability.

With the above mentioned and other objects in view, the invention consists in the novel construction and combination of parts hereinafter described, illustrated in the accompanying drawing, and set forth in the claims hereto appended, it being understood that various changes in the form, proportion, size and minor details of construction within the scope of the claims may be resorted to without departing from the spirit or sacrificing any of the advantages of the invention.

Referring to the drawing:

Fig. 1 represents a side elevation of a sifter constructed in accordance with my invention,

Fig. 2 represents a fragmentary vertical sectional view of the sifter.

Fig. 3 represents a horizontal section on line 3—3 of Fig. 1.

Referring in detail to the drawing wherein one embodiment of the invention is illustrated, 1 designates the cylindrical body portion of a sifter, which body portion is formed of some light, dust-proof metal and one side is provided with the usual handle 2. Mounted at the lower end of the body

portion is a concavo-convex screen 3, which is removably supported in the lower end of the sifter and in view of its disposition at said lower end provides for the sifter holding a greater quantity of flour than is possible in sifters having the perforated walls spaced well inwardly from the lower end. The screen 3 is provided at spaced points on its periphery with projections 4 adapted to engage in notches or slots 5 extending upwardly from the lower edge of the body portion 1. These projections 4 engage snugly in the notches and prevent turning of the screen or rattling thereof but permit of ready removal of said screen. The screen is held in place by a pair of supporting rods 6 which extend across opposite sides of the screen beneath the latter through openings 7 and 8 provided in the body portion 1. The rods are provided at certain ends with head portions 9 and at their other ends are screw threaded as at 10 whereby nuts 11 may be turned on the threaded ends to hold the rods in place. The arrangement is such that the rods will be flexed and placed under slight tension when in place in the openings 7 and 8, and engaged with the lower side of the screen whereby the screen will be securely held in place. The preferable arrangement of the rods is to extend them from slightly spaced points on one side of the body portion divergently to the other side of the body portion as shown particularly in Fig. 3, whereby an adequate supporting of the screen will be provided for. Extending upwardly from the center of the screen is a pin 12 on which the hub portion 13 of the agitator 14 is rotatably mounted. The agitator comprises a plurality of tangentially extending arms 15 curved to conform to the concavity of the screen and adapted to lie close to the upper surface of the latter. One of the arms 15 is bent as at 16 near its outer end and extended through an arcuate slot 17 provided between the body portion and a recessed portion of the screen. After being thus extended the portion 16 is extended outwardly to serve as a handle 18 there being provided in the wall of the body portion an arcuate slot 19 through which the portion 18 extends. By grasping the handle 18 and moving it back and forth, the agitator will be moved over the screen to cause the flour to sift in the usual manner. The agitator of my invention and the screen are so constructed and associated with one

another and the body portion that in operation the flour will not be thrown out of the top of the can but will be effectively sifted through the screen.

5 When it is desired to clean the screen and its associated parts, it is only necessarily to withdraw the rods 6 after removal of the nuts 11, and to allow the screen to drop out of the bottom of the body portion. It will 10 thus be seen that the assembling of the parts may be expeditiously effected as well as the disassembling.

By having the arcuate slots in the body portion or container 1 disposed below the 15 plane of the screen and the slot between the screen and wall comparatively narrow, the flour is, to a great extent, prevented from passing out through the container slot during the operation of the sifter.

20 I claim:

1. A flour sifter comprising a container having slots at the lower end, a screen removably mounted within the lower end of the container, a plurality of projections 25 on the screen engaging in the slots and removable supporting members extending across the lower end of the container beneath and supporting said screen in place.

2. A flour sifter comprising a container 30 having slots at the lower end, a screen removably mounted within the lower end of the container, a plurality of projections on the screen engaging in the slots, removable

supporting members extending across the lower end of the container beneath and supporting 35 said screen in place and an agitator mounted within the container close to the upper side of the screen.

3. A flour sifter comprising a container having slots at the lower end, a screen removably mounted within the lower end of the container, a plurality of projections on the screen engaging in the slots, removable supporting members extending across the lower end of the container beneath and supporting 40 said screen in place, an agitator mounted within the container close to the upper side of the screen, said container having a slot adjacent its lower end and an extension from the agitator slidably engaged 45 in said slot.

4. A flour sifter comprising a container having slots at the lower end, a screen removably mounted within the lower end of the container, a plurality of projections on the screen engaging in the slots, removable supporting members extending across the lower end of the container beneath and supporting 55 said screen in place, an agitator mounted within the container close to the upper side of the screen, said container having a slot adjacent its lower end and an extension from the agitator slidably engaged 60 in said slot, said slot being below the plane of the screen.

AUGUST Z. BOSE.
